Primary Examiner — Mojtaba Tehrani

(57) **CLAIM**

The ornamental design for a firearm chassis, as shown and described.

DESCRIPTION

FIG. 1 is perspective view of an exemplary firearm chassis from the left and above toward the rear.

FIG. 2 is a perspective view of the firearm chassis of FIG. 1 from the right and above toward the rear.

FIG. 3 is a left elevation view of the firearm chassis of FIG. 1.

FIG. 4 is a right elevation of the firearm chassis of FIG. 1.

FIG. 5 is a bottom plan view of the firearm chassis of FIG. 1.

FIG. 6 is a top plan view of the firearm chassis of FIG. 1.

FIG. 7 is a front elevation view of the firearm chassis of FIG. 1; and,

FIG. 8 is a rear elevation view of the firearm chassis of FIG. 1.

The broken lines in the drawings disclose unclaimed portions of the firearm chassis only and form no part of the claimed design.

1 Claim, 4 Drawing Sheets
